UNITED STATES PATENT OFFICE

2,482,770

WINDOW FOR PRESSURE CHAMBERS

Arnold H. Heineman, Chicago, Ill., assignor, by
mesne assignments, to Guardite Corporation,
Wilmington, Del., a corporation of Delaware

Application July 11, 1945, Serial No. 604,433

6 Claims. (Cl. 98—29)

1

This invention relates to a window for a pressure chamber, and more particularly to such a window that will withstand the pressure in such a chamber, but permit clear vision therethrough.

A pressure chamber is subjected to extremes of temperature and humidity, and to a wide range of atmospheric pressure conditions. The window through which the effect of these conditions on the material being tested is viewed must be clear at all times and must be able to withstand the above variations which tend to expand and contract the glass in the window as well as to subject it, at times, to wide differences in pressure.

This invention will be described in detail as set out in the embodiment shown in the accompanying drawings, in which:

Fig. 1 is a plan view of the window in a fragmentary section of the chamber,

Fig. 2 is a sectional view taken on the line 2—2 of Fig. 1; Fig. 3 is a sectional view along line 3—3 of Fig. 1, and Fig. 4 is a view of the complete vacuum chamber partly broken away for clarity of illustration.

In the fragmentary embodiment shown the pressure chamber is indicated at 10 and comprises an outer pressure sustaining wall 11 and an inner flexible diaphragm 12 which define a space 13 between them. Means are provided for evacuating the pressure chamber within the inner wall 12 and also the chamber 13 between the walls 11 and 12, the means comprising a pipe 8 adapted to be connected to an evacuating device (not shown) and opening to the inner chamber; and a second pipe 9 adapted to be connected to such vacuum producing device and opening to the chamber between the walls 11 and 12. A window frame 14 is hermetically welded in an opening in these walls. This frame consists of an outer section 15 and an inner section 16 separated by a ring 17a of diathermal material—preferably of plastic. The frame may be suitably welded to the walls 11 and 12. The sections 15 and 16 and the ring 17a are held in assembled relationship by the means indicated in Fig. 3, comprising a bolt 41 countersunk in the member 16 and threading into a threaded portion of the ring 17a. A second bolt 40 is countersunk in the ring 17a, as shown, and threads into a threaded portion of member 15. In assembling the above described members, the ring 17a is positioned over the section 15 and secured thereto by the insertion and tightening of bolt 40, then the section 16 is placed in position over the ring 17a and held in that position by the bolt 41. It can be seen that no metal is continuous between the members 15 and 16, the bolt 40 being in contact with the members

2

15 and 17a only, while bolt 41 contacts only members 16 and 17a. Within the frame are two sets of glass panels 17, 18, 19 and 20, 21, 22. In the middle of the sets is a gasket or stop member 24 which separates the panes and forms a chamber 25 which is connected by openings 26 to the chamber 13. Openings 27 and 28 are likewise provided connecting the chamber 25 with the space between the panes 19 and 18, and between the panes 18 and 17. The panes are separated from each other and from the various gaskets and stop members by rubber gaskets 29. The panes are held in the frame by flanged bars 30 and 31 attached respectively to the inner and outer sides of the frame. They may be secured to the frame by any suitable means such as the bolts 32 and 33.

All of the panes are spaced from the frame member at their edges, as indicated at Fig. 2. This may be accomplished by positioning the panes in proper relationship to the sides of the frame and placing thin strips between the frame and the bottom of the panes prior to attaching the flanged bars to the top and sides of the frame. The side and top bars will hold the panes in place, while the bottom bars are attached. The flanged bars are, however, spaced from the metal frames so that an annular opening may be provided connecting the edges of the panes with the interior of the chamber or the outside atmosphere. I have, however, indicated a gasket 34 in connection with the flanged bar 30 sealing off this connection from the pressure chamber.

The panes of glass, as assembled, do not contact the metal frame at any point, nor is there any direct contact between the panes and the retaining flange bars. Furthermore, the relatively great changes in temperature in the chamber, which are quickly taken up by the metal wall and window frame, are not transmitted to the panes by these members. Hence, the pane may expand without danger of cracking.

The hollow wall of the chamber is evacuated to insulate the chamber, and the passageway 26 between the two sets of glasses, being connected with said wall, is likewise evacuated. This results in a uniform pressure being exerted against the front set of panes. The vacuum in the chamber wall should not be exceeded by the vacuum in the chamber to any great extent; hence the difference in pressure against the inner set of panes is never excessive.

The function of the passageways 27 and 28 is to prevent condensation upon the faces of the panes 17, 18 and 19. The evacuation of the inner chamber produces a drop in temperature of that

chamber and therefore produces a cooling of the pane 17. This cooling would, in the absence of passageways 27 and 28, cool the air in the space between panes 17 and 18 with the consequent condensation of moisture upon the glass. However, inasmuch as the space between the walls is evacuated along with the inner chamber and that space is connected by passageways 26, 27 and 28 with the space between the panes 17 and 18, the pressure in that space is also reduced with the result that the humidity is unchanged, and there is no great difference between either the temperature or the humidity on opposite faces of any one inner pane. Thus, the possibility of condensation is practically eliminated.

The foregoing detailed description has been given for clearness of understanding only, and no unnecessary limitations should be understood therefrom.

What I claim as new, and desire to secure by Letters Patent, is:

1. In a pressure vessel, an outer pressure sustaining wall, a gas tight inner diaphragm spaced therefrom and surrounding a vacuum chamber, means for evacuating the vacuum chamber and the space between the wall and the diaphragm, a window frame sealed to the wall and the diaphragm, said window frame including an insulating compression ring dividing the frame into exterior and interior portions, and a series of spaced window panes within the frame, at least one of said panes sealing the outer atmosphere from the vacuum chamber.

2. A vessel as set forth in claim 1 in which the compression ring is on the inner side of at least one sealing pane.

3. A vessel as set forth in claim 1 in which at least four panes are provided in parallel relationship and there is a chamber between the central panes, said chamber having an opening therein

communicating with the space between the wall and the diaphragm.

4. A vessel as set forth in claim 1, in which a series of six panes in parallel relationship is provided, there is a central chamber between the third and fourth panes, said chamber having an opening therein communicating with the space between the wall and the diaphragm, and openings are provided through the second and third pane from the interior to said central chamber.

5. A vessel as set forth in claim 1, in which all of the panes are spaced at their edges from the frame.

15 6. A vessel as set forth in claim 1, in which at least four panes are provided in parallel relationship and there is a chamber between the central panes, said chamber having an opening therein communicating with the space between the wall and the diaphragm and in which the panes interior of the chamber are provided with an opening communicating with the chamber and with the spaces between the panes.

ARNOLD H. HEINEMAN.
